UNITED STATES PATENT OFFICE

2,692,402

APPLICATOR FOR COATING LIQUIDS

Georges Gabriel Marie Dechaux, Paris, France

Application September 27, 1949, Serial No. 118,172

Claims priority, application France
December 27, 1948

5 Claims. (Cl. 15—127)

1

This invention relates to a device for the application of a coating liquid, such as a paint, a varnish and the like, in the form of thin layers or films onto a surface by causing an applicator to travel on a strip or band of the surface under treatment.

By means of this device a continuous primary film of desired width, composition and viscosity is applied onto a surface expelling objectionable mediums, such as air and water, from between the film and the surface while pressing the primary film against the same to cause a mutual adherence, applying onto the primary film immediately after the pressure application a second continuous film, which has the same width and the same, or a different composition than the primary film, and controlling the thickness of the second film to cause the latter to adhere to the primary film.

The invention will now be described with reference to the accompanying drawings, which illustrate, more or less diagrammatically, several modifications of the same.

In the drawings:

Fig. 1 is a diagrammatic showing of a painting device according to the present invention;

Fig. 2 is a detailed elevational view, in cross-section, of a modification of the device diagrammatically shown in Fig. 1;

Fig. 3 is a front view, partly in section, corresponding to Fig. 2, with parts broken away for the sake of clarity;

Fig. 4 is a cross-sectional view, with a part broken away, of another form of painting device according to the invention;

Fig. 5 is a cross-sectional view showing a form of the spreader;

Fig. 6 is a perspective view showing another form of spreader;

Fig. 7 is a diagrammatic showing of a further form of a paint applying apparatus designed in accordance with the invention.

Referring first to Fig. 1, it will be seen that the liquid paint 1 under pressure flows into a container 4 through a flexible pipe 2 provided with a stop or regulation valve 3 that may be adapted to serve as a control-handle.

A vertical spreader 6 is inserted into the bottom of the container 4. The lower end 7 of the spreader 6 projecting from the container 4 is half-cylindrical in shape; it is intended to be applied against the surface under treatment 8 for the purpose to apply to this surface a priming film of paint 9, the latter being formed when the apparatus is advanced in the direction of the arrow

19, the liquid paint flowing under pressure from the container 4 down through holes 11, made in the container bottom ahead of the spreader 6, into a space 12 defined by said bottom blade and a resilient blade 13 having its upper edge affixed to the container 4 and its lower edge resiliently applied against the spreader 6 or its mounting, and from said space 12 down onto the surface 8 through a suitable passageway made for the paint, in close proximity to the surface 8, between the spreader 6 or its mounting and the lower edge of the resilient blade 13; the formation and spreading of the priming film takes place concurrently with the displacement of the apparatus in the direction of arrow 19.

Behind the spreader 6 the liquid paint under pressure 1 flows down through holes 17 into a space 15 defined similarly to the space 12 by a second resilient blade 16, which is more or less removed away from the spreader 6, whose lower edge 17, extending parallel with the surface under treatment 8, permits the liquid paint flowing down from the space 15 to coat the priming film 9 spread, as above stated, by the spreader 6 and regulates the total thickness 18 of the two superposed films.

The width of the two films may be controlled by providing the spaces 12 and 15 with suitable end walls (not shown) parallel to the plane of the paper, or by the factors influencing the flow of the liquid paint through the said spaces, such as the number and sizes of holes 11 and 14 and the location, nature and elasticity of the blades 13 and 16.

The operation of this apparatus is as follows: The apparatus being displaced in the direction of the arrow 19 and its spreader 6 being applied against the surface 8, the liquid paint flowing down from the space 12 against the spreader 6 is laminated between the spreader surface 7 and the surface 8, the air or other ambient medium being expelled forward, so that the adherence of the priming film 9 to its support is fully assured.

The elastic deformation of the spreader end 7 enables application of the paint even onto projections from the surface 8, such as rivet heads or variations in normal thicknesses. Since the space 15 is filled with liquid paint, the entrance of air or of another ambient medium is prevented and the final layer of paint takes the form of a film 18, incorporating the priming film 9, the total thickness of which is regulated by the distance between the edge 17 of resilient blade 16 and the surface 8. The deformation of the blade 16, particularly near its edge 17, is such as to per-

3

mit the latter to pass over projections and rivets extending from the surface 8.

In Figs. 2 and 3 there is shown in detail a modification of the apparatus of Fig. 1. The spreader 6' has a cylindrical shape and is inserted into a cylindrically shaped housing 5 welded at 21 to the container 4 composed of two cylindrical parts 22 and 23, with their axes respectively parallel and perpendicular to the surface 8 to be painted. The resilient blades 13 and 16 are affixed, by means of screws such as 25, to the cylinder 22 having its ends closed by means of walls 24. The holes 11 and 14 are conveniently spaced along the cylinder 22 and adapted to direct the liquid paint 1 to the spaces 12 and 15, respectively, and therefrom along the spreader at 31 and 32 to form the priming film 9, adhering to the surface 8, and the second film 18, of a thickness regulated by the lower edge 17 of blade 16, by which this priming film is coated immediately.

The flow of the liquid paint 1 is controlled by a mechanism described in the following: A valve disc 33 is mounted on the central extension 34 of a bar 35 diametrically affixed to the cylinder 22 by means of screws 25. The seat for this valve disc is disposed upon the bottom 37 of a cylindrical part 38 topped by a part 39 screwed thereon as at 41. By downwardly screwing the part 39 it is possible to regulate the compression of a spring 42 that tends to apply the valve disc 33 against its seat 36.

The valve disc 33 is centered by means of ribs 43 and its stroke, with respect to the seat 36, is limited by the abutment 45 adapted to act upon the upper end of the valve rod 44.

The part 39 is pierced with liquid paint feed openings 46 and has its upper portion threaded as at 47 to receive a fitting 48 (Fig. 2) adapted for connection with the corresponding end of a flexible pipe (not shown) intended to supply the apparatus with liquid paint under pressure from a feed tank not shown.

The cylindric part is slidably guided by ribs 49 arranged in the cylinder 23.

A screw-threaded collar 51 and a U-shaped annular leather packing 52 provide a tight joint for the passage of the cylindrical part 38 outside of the ribs 49, the part 38 being prevented from rotation by means of lugs 53 (Fig. 2) rigidly connected with the cylinder 23.

The operation of this apparatus is, as follows. When the apparatus is applied by the operator against the surface under treatment 8 with a sufficient force to deform the spring 42, the liquid paint passes into the cylinder 22 and, through the holes 11 and 14, into the spaces 12 and 15. When the apparatus is then moved in the direction of the arrow 19, the spreader 6' causes the priming film 9 to adhere to the surface 8, while the edge 17 causes a second film to immediately coat the priming film 9, whereby a compound layer of paint 18 is produced whose thickness E is regulated by the edge 17, without the air or other medium being adapted to interpose itself between the two films. In this way perfect coating is obtained by a single passage of the apparatus.

Owing to a flexible feed pipe, the liquid paint under pressure may be fed into the apparatus with the aid of any suitable outside feeding means. Such an apparatus is particularly suitable for painting large surfaces or for an extensive serial work.

Shown in Fig. 4 is a form of painting apparatus

4

in which a limited quantity of liquid paint is confined alone in the container 4 which here is cylindro-spherical in shape, the cylinder 61 being open at its top so as to receive a corresponding cylindro-spherical piston 62 directed by outside guides 63 and tightened by a packing ring 64.

The lower half-sphere 65 carries, as in Fig. 2, the spreader 6' and two resilient blades 13, 16. The spreader 6' is inserted into the housing 5 having a length corresponding to that of the blades 13, 16.

The bottom 65 of container 4 has paint outlets 11, 14 and may be provided with a filtering wire-screen 66. The operation of this apparatus is analogous to the one described above, the liquid paint in the container 4 being set under pressure by the operator acting upon the piston 62 by means of a handle 67, of which only the connection with the piston 62 is shown in the drawing.

The pressure exerted by the operator causes the spreader 6' to press against the surface 8; at the same time the apparatus is displaced by the operator in the direction of the arrow 19.

Diagrammatically shown in Fig. 5 is a cylindrical form of spreader for use in painting apparatus, such for example as those shown in Figs. 2, 3 and 4. In this case the spreader has the shape of a thick plate 71, made for example from soft porous rubber, disposed around a suitable core 70 and pasted onto the inner surface of the cylindrically shaped housing 5.

Instead of being pasted, a spreader of this kind may be mounted on bearings so as to rotate when spreading the priming film. The experience, however, teaches that the rotating spreaders, when passing over rivets and the like, are actually caused to rotate. So use will be made, preferably, of non-rotating spreader members like those described hereinabove.

An advantageous form of spreader is shown in Fig. 6. Here the spreader has again the form of a thick plate 71' which is made from elastic and deformable material, such as soft porous rubber, but is U-shaped and confined in a parallelopiped-like housing 72 carried by the container 4.

To render the operative surface of the spreader smoother, the outer wall of the rubber 71' is provided with a lining diagrammatically indicated by a dotted line 73 in the drawing, said lining being fitted into the housing 72. This lining may be made from any suitable flexible material of convenient thickness, such as nylon or other plastic material. Of course, this material should have the requisite mechanical qualities at points of its contact with the coating materials applied by the apparatus.

Diagrammatically shown in Fig. 7 is a form of painting apparatus in which two different coating materials are used, namely an adhesive and a paint, for example.

The container 4 is divided by a center partition 82 into two compartments 83 and 84. Each of these compartments is pressure-supplied with a coating liquid supplied through the feed pipes 85, 86.

The various forms and parts of apparatus hereinabove described and shown should not be construed in a limiting sense, as the same may be modified in various particulars without departing from the spirit of the invention.

What is claimed is:

1. A unidirectionally traveling device for the successive spreading of superposed coatings to a surface comprising a container for the accommodation of at least one coating liquid, at least

one tube attached to said container for the pressure supply of said coating liquid into the container, a resiliently deformable spreader for the distribution of two successive layers of said coating liquid to cover said surface, said spreader being fixedly located in the center portion of the container bottom and downwardly projecting from the same, openings in the bottom of said container for the downward passage of the coating liquid simultaneously onto the advance and the opposite rear face of said spreader, resilient guide blades fastened to the bottom portion of said container and downwardly projecting from the same towards the surface to be covered in order to direct said coating liquid onto the latter, said guide blades forming an advance blade and a rear blade and being located in front of the advance face and in the rear of the opposite rear face of said spreader being bent with their ends towards the same and forming therewith passages for the delivery of the coating liquid onto said surface, whereby a first layer of coating liquid applied to said surface is spread by the passage of said spreader, a second layer of coating liquid is immediately applied on top of said first layer and mutual adherence is secured between said two layers and said surface.

2. In a unidirectionally traveling device according to claim 1 wherein the bottom of the container for the coating liquid has an upwardly extending center bend for the accommodation of the upper portion of the correspondingly shaped spreader.

3. A unidirectionally traveling device according to claim 1 wherein the advance blade is shorter than the rear blade.

4. In a unidirectionally traveling device according to claim 1 a vertical wall in said container to divide the same into adjacent advance and rear compartments and supply tubes for the coating liquids attached to each compartment.

5. In a unidirectionally traveling device according to claim 1 wherein the passage between the advance blade and the spreader is smaller than the passage between the rear blade and the spreader.
